CLAIM

The ornamental design for a self defense phone case, substantially as shown and described.

DESCRIPTION

FIG. 1 is a bottom-left-front isometric view of a self defense phone case,

FIG. 2 is a top-right-back isometric view thereof,

FIG. 3 is a bottom view thereof,

FIG. 4 is a top view thereof,

FIG. 5 is a left view thereof,

FIG. 6 is a right view thereof,

FIG. 7 is a front view thereof,

FIG. 8 is a back view thereof; and,

FIG. 9 is a top-right-front isometric view thereof.
